LOCK LATCH

Milton H. Wells, Scarsdale, N. Y.

Application May 29, 1936, Serial No. 82,410

1 Claim. (Cl. 232—41.1)

My present invention relates to locks and latches and more particularly to an improved combined container and lock.

My present invention is particularly applicable for use in connection with containers, such as milk bottle containers, where the container is to have placed therein some time during the night or early morning one or more full bottles of milk by a person who ordinarily will not have access to the container by means of a key. The key to the container will ordinarily be held in the possession of the householder who at the proper time will manipulate the lock by means of such key and remove the filled milk bottles therefrom, and then either leave the container empty or place therein empty milk bottles. It is therefore necessary to have a container so constructed and arranged that when no milk bottles are in the container, or if in the container, are empty, the cover thereof will not be placed in locked condition and may be opened or closed at any time. When, however, full milk bottles are placed within the container the lock must be placed in such condition that upon subsequent closing of the cover, such cover will be retained in locked position until the lock is manipulated by means of a key.

A feature of my invention is an improved combined container and locking device therefor.

A feature of my invention is an improved locking latch.

Another feature of my invention is an improved locking latch for a container and in combination with means for manipulating the locking latch.

In the accompanying drawing,

Fig. 1 is a perspective view of a container and locking latch therefor embodying my invention.

Fig. 2 is a sectional side elevation, on an enlarged scale, taken on the line 2—2 of Fig. 1.

Fig. 3 is a sectional elevation on the line 3—3 of Fig. 2, and

Fig. 4 is a detail of the locking latch.

Referring to the drawing, 10 designates a casting of any suitable type and adapted to contain any suitable material, but as shown, such container is preferably rectangular in shape and is adapted to have placed therein a plurality of milk bottles as indicated by the reference numeral 11. Such container 10 is provided with a hinged cover 12 and which cover has attached to the under face thereof by rivets 13 a lock catch 14. The lock catch 14 cooperates with a lock bolt 15 forming a part of a lock 16.

The container 10 has hingedly mounted thereon in one wall thereof adjacent the bottom, a

false bottom 17. The free end of the false bottom 17 is provided at each end with a spacing member 18 for maintaining the same substantially parallel to the bottom of the container 10 when milk bottles are placed on the false bottom. Surrounding each of the spacing members 18 is a coil spring 19 which tends to rotate the free end of the false bottom 17 upwardly about the hinge connection.

Formed on the false bottom 17 substantially intermediate the ends thereof are spaced ears 20 in which is pivotally mounted the lower end of a rod 21. The rod 21 extends upwardly and is slidably mounted in a guideway 22 secured to the inner face of the front wall of the container 10 and such rod 21 terminates at a point adjacent to the lock 16.

The lock 16 may be of any desired type, in the present instance the usual ward type, in which there is pivotally mounted at its lower end the lock bolt 15. Such lock bolt is provided with a bevelled surface 23 with which the lower end of the lock catch 14 may engage and with a notch 24 which engages with the lock catch 14 to lock the cover 12 in locked position. Also the bolt 15 is provided with a lateral extension 25 which extends through a slot formed in the casing of the lock 16 and terminates at a point adjacent to but slightly above the rod 21, as clearly shown in Figures 2 and 3. Also the bolt 15 is provided with a bevelled face 26 which is adapted to be engaged by a pin 27 mounted on and movable with the bolt plate 28 of the lock 16. The bolt 15 is constantly urged to rotate in a clockwise direction about its pivot point by a spring 29. The bolt plate 28 is operated by the usual key which operates the wards 30 and is moved downwardly from the position shown in Fig. 3 thereby moving the pin 27 downwardly, and such pin engaging with the bevelled surface 26 rotates the bolt 15 in a counter-clockwise direction to remove the notch 24 from engagement with the lock catch 14 thus permitting the opening of the cover 12.

When the milk bottles 11 are empty, or are removed from the container 10, the springs 19 rotate the false bottom 17 so as to move the same and therefore the rod 21 upwardly, and the upper end of such rod 21 engaging with the lateral extension 25 will rotate the bolt 15 in a counter-clockwise direction so as to maintain the notch 24 thereof out of engagement or out of the path of movement of the lock catch 14 while the above conditions prevail. It is therefore possible for the owner of the container 10 after having opened the container, to remove the full milk

bottles 11, and to either leave the container 10 empty or put in such container empty milk bottles 11 and to then remove the operating key and yet leave the interior of the container accessible to the milkman or other authorized person.

Immediately the milkman or other authorized person places within the container 10 filled milk bottles 11 or other merchandise sufficient in weight to compress the springs 19 and lower the level of the false bottom 17 within the container, the rod 21 will be moved downwardly out of engagement with the lateral extension 25 and thereby permit the spring 29 to rotate the bolt 15 in a clockwise direction and into position to have the notch 24 thereof engage with the lock catch 14. If however, the cover 12 is not at this time closed, the latch 15 will be in its locking position but the movement of closing the cover 12 will cause the lock catch 14 to ride on the bevelled surface 23 of such bolt 15 and will move the bolt against the tension of the spring 29 sufficient to allow the lock catch 14 to ride into engagement with the notch 24.

Whereas I have described my invention by reference to specific forms thereof, it will be understood that many changes and modifications may

be made without departing from the spirit of the invention.

I claim:

In a combined container and lock the combination of a container body, a hinged platform within said body, resilient means for urging the free end of said platform upwardly, an operating rod pivotally attached to the free end of said platform, a guideway secured to the front of the container and engaging with the operating rod intermediate its ends for constraining and guiding the operating rod to move in a vertical path, a lock mounted on the front face of the container, a pivotally mounted lock bolt forming a part of said lock, a lateral projection on said lock bolt for rotating the same, said projection on the lock bolt lying normally in the path of movement of the operating rod and physically disconnected therefrom and out of engagement therewith when the platform is in its lowermost position, and adapted to be engaged by said operating rod to rotate the said lock bolt to unlocked position when the platform is moved from its lowermost to its uppermost position.
